[57] CLAIM

The ornamental design for a computer cabinet, as shown and described.

DESCRIPTION

FIG. 1 is a front perspective view of a computer cabinet showing our new design;

FIG. 2 is a side elevational view thereof, the undisclosed elevational views being identical in appearance;

FIG. 3 is a top plan view thereof;

FIG. 4 is a front perspective view of a second embodiment of the design;

FIG. 5 is a side elevational view thereof, the undisclosed elevational views being identical in appearance;

FIG. 6 is a top plan view thereof;

FIG. 7 is a front perspective view of a third embodiment of the design;

FIG. 8 is a side elevational view thereof, the undisclosed elevational views being identical in appearance; and,

FIG. 9 is a top plan view thereof.
